United States Patent Office

Des. 179,794
Patented Mar. 5, 1957

179,794

SCALE

Kenneth C. Allen, Dayton, David A. Meeker, Troy, and Ernest A. Reussenzech, Dayton, Ohio, assignors to The Hobart Manufacturing Company, Troy, Ohio, a corporation of Ohio

Application May 12, 1953, Serial No. 24,961

Term of patent 14 years
(Cl. D52—10)

Fig. 1

Fig. 2

Fig. 3

Fig. 4

Fig. 1 is a perspective view showing the front of a scale embodying our new design;

Fig. 2 is a perspective view showing the back of the scale; and

Figs. 3 and 4 are, respectively, side and front elevational views of the scale.

The characteristic features of the design reside in the portions shown in full lines.

We claim:

The ornamental design for a scale, substantially as shown and described.
